[57] CLAIM

The ornamental design for a battery adaptor for a portable video camcorder battery pack, as shown and described.

DESCRIPTION

FIG. 1 is a front and upper right perspective view of a battery adaptor for a portable video camcorder battery pack showing my new design;

FIG. 2 is a front and upper right perspective view thereof, shown with a battery pack attached, the broken line showing of the battery pack is included for the purpose of illustrating environmental elements only and forms no part of the claimed design;

FIG. 3 is a right-side elevational view thereof;

FIG. 4 is a left-side elevational view thereof;

FIG. 5 is a bottom plan view thereof;

FIG. 6 is a rear elevational view thereof;

FIG. 7 is a front elevational view thereof; and,

FIG. 8 is a top plan view thereof.

*FIG. 1**FIG. 3**FIG. 2**FIG. 4**FIG. 5**FIG. 6**FIG. 7**FIG. 8*
